US0D1066333S

(12) **United States Design Patent** (10) **Patent No.:** **US D1,066,333 S**
(45) **Date of Patent:** **** Mar. 11, 2025**

(54) **DISPLAY DEVICE**

(71) Applicant: **Google LLC**, Mountain View, CA (US)

(72) Inventors: **Jason Stanley Pi**, Fremont, CA (US); **Maj Isabelle Olsson**, Sunnyvale, CA (US); **Carl Cepress**, Los Altos, CA (US); **Bengt Gunnar Brümmer**, San Francisco, CA (US); **Fred Simon**, San Francisco, CA (US); **Ethan Alexander Graves**, Santa Clara, CA (US); **Vivek Saini**, Sunnyvale, CA (US)

(73) Assignee: **Google LLC**, Mountain View, CA (US)

(**) Term: **15 Years**

(21) Appl. No.: **29/838,014**

(22) Filed: **May 10, 2022**

(51) LOC (15) Cl. **14-02**

(52) U.S. Cl.

USPC **D14/341**

(58) **Field of Classification Search**

USPC ..... D14/336, 341, 342, 343, 371, 374, 389, D14/138 R, 138 AA, 138 AB, 159, 126, D14/129
CPC G06F 1/1681; G06F 1/1613; G06F 1/1615; G06F 1/1626; G06F 1/1652; H04M 1/0268
